[57] CLAIM

The ornamental design for a pitot tube type sensor, as shown.

DESCRIPTION

FIG. 1 is a top, front and left side perspective view of a pitot tube type sensor showing my new design, the broken line showing of an attached instrumentation mechanism is for environmental purposes only and form no part of the claimed design;

FIG. 2 is a front elevational view;

FIG. 3 is a right side elevational view;

FIG. 4 is a rear elevational view;

FIG. 5 is a top plan view; and,

FIG. 6 is a bottom plan view thereof.
